UNITED STATES PATENT OFFICE.

FRANK DUTCHER, OF VERSAILLES, PENNSYLVANIA, ASSIGNOR TO CENTRAL RAILWAY SIGNAL COMPANY, OF PITTSBURGH, PENNSYLVANIA, A CORPORATION OF NEW JERSEY.

METALLIC RAILWAY SIGNAL-TORPEDO.

1,284,620.

Specification of Letters Patent.

Patented Nov. 12, 1918.

Application filed August 9, 1917. Serial No. 185,302.

To all whom it may concern:

Be it known that I, FRANK DUTCHER, a citizen of the United States, residing at Versailles, in the county of Allegheny and State 5 of Pennsylvania, have invented certain new and useful Improvements in Metallic Railway Signal-Torpedoes, of which the following is a specification, reference being had therein to the accompanying drawing.

10 My invention relates to improvements in metallic railway signal torpedoes.

The object of my invention is to provide a torpedo of this character of a thin sheet of lead foil or other metal which, when exploded, is fused by the heat from the explosive compound, throwing it off in fine flakes or particles and thereby avoiding injury from any flying parts of the metal from the torpedo.

20 Another object of my invention is to provide a simple, cheap and effective torpedo having certain details of structure and combination of parts hereinafter more fully set forth.

25 In the accompanying drawings—

Figure 1 is a bottom perspective view of my improved metallic railway torpedo.

Fig. 2 is a vertical transverse sectional view.

30 Fig. 3 is a perspective view of the several parts of which my torpedo is formed, showing them in their separated relation.

Fig. 4 is a bottom perspective view of a modified form of torpedo embodying my invention.

Fig. 5 is a vertical transverse sectional view of the form of torpedo shown in Fig. 4.

Fig. 6 is a perspective view of the several parts of which my torpedo is composed, showing them in their separated relation.

Fig. 7 is a bottom plan view of the form of torpedo shown in Fig. 1, and showing part of the closing disk broken away.

Fig. 8 is an enlarged vertical sectional view of a portion of the torpedo.

Referring now to the drawings, 1 represents the main body portion of my improved torpedo, which is preferably made of very thin sheet lead foil and stamped from a 50 disk of said foil and having its ends extending downwardly, as shown in Fig. 3 of the drawings. This sheet of lead foil is made very thin so that the heat from the explosive compound will fuse the same so

that there will be no flying particles upon 55 the explosion of the explosive compound. The explosive compound 2, as shown, is in tablet form and is placed within the body portion 1, from below, as will be readily understood by reference to Fig. 3 of the 60 drawing. After the explosive compound is placed in the body-portion 1, a disk 3 is placed in the body-portion resting against the lower face of the explosive. This disk 3 is provided with two openings 4 and 5, 65 and through which is threaded the rail-attaching strap 6. The openings 4 and 5, as shown, are spaced some distance from the edge of the disk, so that the lower edge of the body-portion can be crimped inwardly 70 upon the disk as indicated at 7, Fig. 1.

The disk 3 is preferably held against the explosive compound 2, by means of a thin film of water-proofing material, as indicated at 8, Fig. 2, so as to prevent any water entering through the slots 4 and 5 from coming in contact with the explosive compound 2. The lower crimped edges 7, of the body of the case, are cemented to the lower face of the disk holding the several parts together 80 and also preventing moisture from entering the case and coming in contact with the explosive compound. The rail-attaching strap 6 is also cemented to the disk and also to the crimped edge 7 of the body-portion, 85 as fully shown in Fig. 2 of the drawings.

In the modification shown in Fig. 4, the body-portion 1 is constructed in precisely the same manner as that shown in Fig. 1, and a disk 8 is first placed in the upper end 90 of the body portion so as to reinforce the top of the torpedo case. The explosive compound 2 is then placed in the case and a disk 9 placed in the case and cemented to the lower face of the explosive compound 2. A 95 disk 10 is then placed in the body-portion against the disk 9 and is provided with the slots 11 and 12 through which is threaded the rail-attaching strap 13. The lower edges of the body-portion are crimped as indicated 100 at 7, the same as in Fig. 1 of the drawing. The rail-attaching strap is cemented to the disk 10 and also to the crimped portion 7 of the body-portion, the same as described in respect to the structure shown in Figs. 1 105 and 2 of the drawings. A fourth disk 14 is then placed over the crimped or folded end 7 of the case and is provided with open-

ings 15 and 16 through which the rail-engaging strap 13 passes, and this disk 14 is tightly cemented to the disk 10 and also to the crimped portion 7 of the body of the 5 torpedo. This disk 14, as shown, forms a torpedo having a smooth lower face and also it provides the necessary strength and base for the torpedo. It will be observed from the foregoing that the member 1 is approximately cup-shaped and the completed torpedo is of a circular box-like form.

From the foregoing description it will be seen that I have provided a metallic torpedo made from a thin sheet of lead foil 15 in which the explosive compound is fully protected and at the same time providing the necessary strength to the case to withstand the ordinary handling of the torpedo. In the form shown in Figs. 1, 2 and 3, including 20 the explosion of the explosive compound fuses the thin lead foil body-portion and absolutely prevents the throwing off of any large parts of the body and thus avoiding injury to anyone standing close to the 25 torpedo when exploded.

In the modification shown in Figs. 4 to 8 inclusive, I have provided the disks 8, 9, 10 and 14 which strengthen both the upper and lower faces of the torpedo, yet producing 30 a torpedo, the sides of which will readily fuse by the heat from the explosion of the explosive compound and prevent the flying of any large particles of the case when the torpedo is exploded. These disks also serve 35 as attaching means for the rail-engaging strap and also protect the explosive compound at its upper and lower faces.

While I have shown and described a torpedo in which the explosive compound is 40 placed therein in tablet form, it will be understood that the same could be in powdered form without departing from my invention.

Having thus described my invention, what 45 I claim and desire to secure by Letters Patent is:

1. A circular box-like torpedo comprising a cup-shaped member composed of foil fusible metal, an explosive therein, a paper disk connected with the explosive by a wa-

terproof cement, the peripheral flange and 50 cup-shaped member cemented to the disk and a rail-attaching member connected with the said disk, whereby a circular box-like torpedo is provided in which its peripheral edge is fusible under the heat of explosion 55 to prevent flying particles.

2. A circular box-like torpedo composed of a metal foil cup-shaped member, an explosive therein, a disk outside of the explosive, the edge of the cup-shaped member 60 turned inward and cemented to the disk, a rail attaching member connected with the disk, the peripheral edge of the circular box-like torpedo composed of thin metal fusible under the heat of explosion, for the purpose 65 described.

3. A circular box-like torpedo comprising a cup-shaped member composed of foil metal fusible under the heat of the explosion, a paper disk in the top of the cup-shaped 70 member and a paper disk at the bottom of the cup-shaped member, an explosive between the disks, a rail attaching member connected with the disk, constituting a circular box-like torpedo having a fusible foil 75 metal peripheral edge, for the purpose described.

4. A torpedo comprising a body-portion made of thin sheet foil, a disk in the upper end of the body-portion, an explosive tablet within the body-portion below the disk, a disk in the body-portion below the explosive compound and cemented thereto, a disk in the body-portion below the last mentioned disk and having parallel slots, a rail-engaging strap passing through said slots, the lower edge of the body-portion crimped over on the last-mentioned disk and a disk cemented to the last-mentioned disk and to the crimped lower edge of the body-portion and having slots through which the rail-engaging strap passes.

In testimony whereof I hereunto affix my signature in the presence of two witnesses.

FRANK DUTCHER.
